TUFTING ATTACHMENT FOR SEWING MACHINES

William F. Schmiedel, Oshkosh, Wis., assignor to
Deltex Rug Company, Oshkosh, Wis., a corpora-
tion of Wisconsin

Application May 14, 1937, Serial No. 142,534

1 Claim. (CL. 112—79,

This invention relates to improvements in tufting attachments for sewing machines.

It is one of the objects of the present invention to provide a tufting attachment adaptable to a standard form of sewing machine and requiring relatively little modification of the sewing machine.

A further object of the invention is to provide tufting attachments of the character described wherein the looper receives its reciprocatory motion directly from the main drive of the sewing machine, while the cutting instrumentality receives its power from an independent source, thereby relieving the main drive of the machine of an undue burden and strain.

A further object of the invention is to provide tufting attachments of the character described which can be arranged for use with either single or multiple needle sewing machines.

Heretofore, in sewing machine tufting attachments, looped threads have been severed by means of cutters which are swung or reciprocated to and from the formed loops. Where the severing of loops is accomplished with cutting instrumentalities of this nature, the formed loops are necessarily severed with a drawing or chopping action of the cutter. The present invention has as another object the provision of a revolving circular cutter mounted on a relatively fixed axis and arranged so that the formed loops are brought into contact with the revolving cutter. This arrangement has the advantages of providing substantially greater cutting edges which are not subjected to undue wear, provides for cleaner and sharper severing of the formed loops, and also results in a construction wherein the cutters are removable without changing or losing the original and proper adjustment or positioning of the cutters relative to the work.

A further object of the invention is to provide a tufting attachment for sewing machines wherein the cutter is susceptible of adjustment in all directions with the advantage that it may be adjusted very minutely relative to the work to properly position it for different types of yarn or thread being utilized and with the further advantage that as the knife edge wears down from usage, this may be compensated for by adjustment of the cutter axis.

A further object of the invention is to provide, in a tufting attachment for sewing machines, a looper which is of very simple construction and which may be machined and mounted in a very simple and expeditious manner, said looper further being formed with an integral guiding sur-

face to act as a supporting guide for the sewing machine needle during certain positions of the same.

A further object of the invention is to provide a tufting attachment for sewing machines where- 5 in the looper is adjustable so that different height piles may be effected in the tufted fabric produced on the sewing machine.

A further object of the invention is to provide an attachment of the class described wherein a 10 previously formed and engaged loop on the looper is severed during a reciprocation of the looper in one direction and at the same time that another loop is being engaged and formed.

A further object of the invention is to provide 15 a tufting attachment for sewing machines which is of very simple construction, is strong and durable and inexpensive, and which is well adapted for the purposes set forth.

With the above and other objects in view, the 20 invention consists of the improved tufting attachment for sewing machines and its parts and combinations as set forth in the claim, and all equivalents thereof.

In the accompanying drawings in which the 25 same reference characters indicate the same parts in all of the views:

Fig. 1 is a fragmentary end elevation of a sewing machine showing the improved tufting mechanism incorporated therein, portions of the ma- 30 chine being broken away and in section;

Fig. 2 is a fragmentary end elevation of a sewing machine having the improved tufting mechanism incorporated therein, with portions of the base of the machine in section, showing a differ- 35 ent position of the needle and looper from that disclosed in Fig. 1, during the formation of a loop and severance of a previously formed loop;

Fig. 3 is a view similar to Fig. 2 only showing the arrangement of the needle and tufting mech- 40 anism during another point of the sequence of operation of the mechanism;

Fig. 4 is a horizontal sectional view taken on line 4—4 of Fig. 1 with certain cover plates re- 45 moved;

Fig. 5 is a longitudinal vertical sectional view taken on line 5—5 of Fig. 4;

Fig. 6 is an enlarged fragmentary detail sec- 50 tional view of the ends of a pair of loopers and showing the position of a pair of needles relative thereto;

Fig. 7 is a detail sectional view taken on line 55 7—7 of Fig. 5; and

Fig. 8 is a detail sectional view taken on line 8—8 of Fig. 2.

Referring now more particularly to the drawings, it will appear that the sewing machine head is indicated generally by the numeral 12 and said head includes a base portion 13. Extended longitudinally below the base 13, mounted in suitable bearings, is an oscillatory drive shaft 14. Said drive shaft receives oscillatory motion from the usual pulley shaft 15 extending through the upper end of the head 12 by the following mechanism: The pulley shaft is driven by the usual pulley (not shown) mounted on its outer end, and the inner end of the pulley shaft, within the upper portion of the head, has fast thereon an end of a crank 16. The outer end of said crank 15 has pivotally secured thereto the upper end of a crank arm 17 and the lower end portion of said crank arm is pivotally secured to a portion of a slotted casting 18, and said casting is mounted fast on an intermediate portion of a lower rocking stud shaft 19. The adjacent end of the drive shaft 14 has fast thereon an arm 20, and the other end portion of said arm carries a block 21 which is movably engaged within the slot 22 in the casting 18. Hence, when the pulley shaft 15 is turned, through the before described connections, oscillatory movement will be imparted to the drive shaft 14.

Above the end of the base 13 opposite the head 12, there are mounted the usual vertical feeding foot and needle carrying rods designated by the numerals 23, 24 and 25 respectively. In the particular exemplification of the invention illustrated, the sewing machine operates a pair of needles 29 and 29' and said needles are depended from a bracket at the lower end of the needle rod 25. It should be understood, however, that the invention is not to be restricted to any particular number of needles employed by the sewing machine, as it is possible to utilize any number of needles within certain ranges and in the latter event, the looping and cutting mechanism, later to be described, will be suited in numbers to the number of needles employed. The rod 23 carries an outer bifurcated element 26 of an improved feeding foot, while the rod 24 carries an inner foot element 27 adapted to be reciprocated in a horizontal path relative to the outer foot element 26. Also, during certain portions of the movement of said foot element 27, it is raised and lowered slightly with respect to the work supporting plate 28 over which it is disposed. Conventional means are employed for jointly reciprocating the rods 24 and 25 vertically and in a slightly orbital path. Inasmuch as the needles 29 and 29' are depended from the rod 25, the same are reciprocated orbitally and vertically relative to slotted openings 33 in the foot element 27. Said needles are also adapted to pass through needle slots 30 in the work supporting plate 28 and into close proximity to the serrated edges 31 and 31' of a yarn engaging plate member 32 secured to the under surface of the work engaging plate adjacent the needle slots 30.

Disposed below the plate 13, transversely thereof and adjacent the needle slot 30, is a slotted supporting bracket 34. Within the slot thereof is slidably mounted a plate 35. One end portion of said plate has longitudinally and vertically adjustably secured thereto (see Figs. 3 and 8) the vertical flange of a right angular looper bracket 36. On the top flange of said looper bracket there are secured in spaced relationship the outer ends of a pair of looper members 37. The inner end of each looper member is bent upwardly and forwardly to provide a hooked portion and at the

extremity of each hooked portion, there is a shoulder 38. It should also be observed that the inner ends and hooked portions of the loopers are slotted, as at 39. During operation of the sewing machine, the needles 29 and 29' reciprocate in an orbital path adjacent the inner face portions of the hooked extremities of the loopers 37, and said inner face portions are slightly dished as at 40 to permit close engagement of the needle ends and to act as supports and needle guides.

As previously mentioned, the drive shaft 14 has an oscillatory movement imparted thereto. The end of said shaft 14 adjacent the looper mechanism, has fast thereon a wheel 41. A block 42 is pivotally secured to the outer face of said wheel 41 in an off-center relationship. Said block, while being free to move on its pivot 43, is slidably confined within a vertical slot 44 in a rear extension of a looper slideable plate 35. Through this connection, therefore, oscillatory movement of the shaft 14 is translated into reciprocatory movement imparted to the plate 35, which plate, carrying the bracket 36 and loopers 37, causes said loopers to move back and forth adjacent the needles 29 and 29' and below the supporting plate 28.

As previously mentioned, the attachment includes a yarn engaging plate member 32 having a pair of spaced end edges 31 and 31' for the purpose of pinching the yarn strands. The plate member 32 is slidably mounted longitudinally of the base 13 immediately below the top surface thereof. An inner portion of said plate 32 carries on its lower surface a depending block 48 which is longitudinally movable in a slot 49 in a lower supporting plate 50. The yarn pinching plate 32 is adapted to slide on the upper surface of said plate 50, between the same and the work supporting plate 28 of the base 13. Mounted fast on the drive shaft 14, below the block 48, is a cam 51 having an eccentric cam groove 52. A cam roller 53 is adapted to ride in said cam groove and said roller is carried by a pin 54 depending from the plate member 32. The cam groove is so shaped, that through the connections with the pinching plate member 32, when the needles 29 and 29' are in raised position, the serrated edges 31 and 31' of the plate 32 will be away from the adjacent edges of the slotted openings in the work supporting plate 28. However, when the needles are in an intermediate position and the loopers positioned so that the loops are engaged by cutting instrumentalities later to be described for severing purposes, the plate 32 moves in a proper direction to pinch the strands of yarn between it and adjacent plate portions so that the formed loops will be held taut during severing operations. During continued travel of the needles and in an orbital path toward the left in the drawings, the pressure foot 26 reciprocates to move the fabric, the movement of the fabric being aided by the orbital movement of the needles toward the left while the needles are passed through the fabric, and during this period, the cam 51 causes a quick short movement of the plate 32 in a direction so as to release the yarn.

Extending longitudinally of the base 13 and below the rear edge thereof is a cutter drive shaft 55 journaled at its ends in suitable bearings. The end of said shaft adjacent the head 12 has fast thereon a pulley wheel 56 engaged by a belt 57 extending to a suitable source of power (not shown). The other end portion of said shaft also carries fast thereon a pulley 58 engaged by a

belt 59, which belt also engages a pulley 60 fast on the free end of a revoluble cutter shaft 61.

On the inner end portion of the shaft 61 adjacent and alined with the slots 39 in the hooked ends of the loopers 37, are a pair of spaced circular or disc, revolving cutters 62 and 62'. Said discs are maintained in spaced relation relative to each other and relative to a bearing block 63 in which the shaft 61 revolves by means of collars 64. Said bearing block is embraced by the U-shaped end portion 65' at the free end of an adjustable arm 65. Normally the block 63 is maintained firmly within said end portion 65' by a releasable clamp 66. However, when said clamp is released, the bearing block, collars 64 and cutters 62 and 62' may be moved or adjusted slightly longitudinally of the shaft 61. This arrangement provides for minute adjustments of the cutters to insure perfect alinement of the same with the slots 39 of the loopers 37 in which the cutters revolve.

There is mounted on the cutter drive shaft 55, one end portion of a bearing bracket 67. The inner face of the other end portion of said bracket is engaged by the shank of the arm 65. This portion of the arm is provided with an elongated slot 68 through which the flattened portion of a bolt 69 extends. The bolt also has a rounded portion which extends through the bracket 67. When the bolt is loosened, the entire arm 65 and parts carried thereby including the cutter shaft 61 and the cutters, may be swung arcuately in a vertical plane. This permits adjustments of the cutters upwardly or downwardly relative to the loopers and the work. Also, by virtue of the slot 68, the arm 65 may be shifted longitudinally and this will advance or withdraw the peripheries of the cutters relative to the loopers and provides for another desirable form of adjustment.

A piece of fabric 70, of a predetermined size to form a rug, is positioned on the base 13 and work supporting plate 28 and the strands of yarn 71, or other material to be used, are threaded through the needles 29 and 29', and when sewed through the material, the same form two spaced apart parallel lines of looped stitching, and the loops of each are cut to form the pile of the rug.

The outer free hooked ends of the loopers are beveled, as shown in Figs. 5 and 6, to permit easy entrance of the same between the needle sides and the strands in forming the loops, and the shoulders 38 at the outer ends of the loopers, prevent the loops from slipping off when the loopers are reciprocated rearwardly, or toward the cutters. In the formation of loops, the strands 71 have upwardly extending portions which engage in notches in the plate 28, and these means serve to hold formed loops tightly on the loopers and prevent slippage when the loopers and feed reciprocate forwardly during upward reciprocation of the needles. Also, the engagement of the yarn strands with said plate is important in connection with the pinching operation of the pinching plate 32 during loop cutting operations, as previously mentioned.

In operation, the needles 29 and 29' having the strands threaded therethrough, reciprocate downwardly through the fabric and through the needle slots 30 of the plate 28. At the lower end of their reciprocation the needles enter the dished portions 40 on the inner faces of the loopers whereby lateral flexure of the needles is prevented. The upward movement of the needles will cause the yarn to slacken, and at the same time, the looper plate, carrying the loopers, will

move forwardly to cause the shouldered ends of the loopers to move between the strands and the needles to a point where the looper shoulders 38 have passed beyond the strands. As the needles rise out of the fabric, the feeding members 26 and 27 operate to push the fabric rearwardly, which movement has been started by the orbital movement of the needles, and the loopers also reciprocate rearwardly, during which time the upwardly extending strand portions of the loops are held taut, as previously described.

In Fig. 1 there is illustrated a needle in its uppermost position with the looper in its forwardmost position. At this stage, a previously formed loop has been forced rearwardly on the looper and another loop is engaged on the looper adjacent the shoulder 38. As the needle moves downwardly, the looper is reciprocated rearwardly toward the revolving cutter 62 until it reaches a point where the previously formed loop is engaged and severed by the cutter, as in Fig. 2, the last formed loop, however, being maintained intact. After this operation, the needle starts to move upwardly and the looper then reciprocates forwardly into a newly formed loop and as the upward movement of the needle is continued and as the looper reciprocates forwardly, the loop thus formed is engaged on the looper, as in Fig. 3. Thereafter, the sequence of operations described is repeated, and it will be observed that only one loop in a row is severed at a time and the looper always has engaged thereon a later formed loop. Obviously, the cut loops form tufts on the fabric, and as the work progresses, said tufts move rearwardly in the elongated needle slot and are accommodated thereby. When the tufts reach the end of the needle slot, they are withdrawn therefrom by a rearward movement of the fabric.

It will be appreciated that with the improved tufting attachments the ordinary drive mechanism for the sewing machine, which is also utilized to reciprocate the loopers, is not subjected to undue strain or overload, because a separate driving instrumentality is utilized for revolving the disc cutters 62, which may be continuously revolved at a high rate of speed. Due to the fact that the cutters are circular, they present much greater cutting surfaces than is found in other forms of cutters for this purpose and there is no undue wear on any one edge portion of the cutter. Due to the fact that the cutters are maintained on a relatively fixed axis and that the loops are reciprocated toward the cutters, the loops are severed with a clean and quick cut instead of by a hacking or chopping action as is the case where reciprocal or pivotal cutters are utilized. The cutters in the present attachments are readily removable for sharpening or replacement, and when it is necessary to temporarily remove a cutter from its shaft 61, the cutter may be readily replaced without losing the position of adjustment of the same, due to the fact that the shaft 61 is fixedly located. As previously described, by adjusting the loopers in a proper direction, the length of the loops and tufts may be easily varied and controlled. Also, the axis on which the cutters revolve may be adjusted in any direction to vary the proximity of the cutter edges to the loopers and work thereon to adapt the instrumentality to different types of yarn or thread, or to compensate for wear on the cutters.

It will be further understood that a number of said tufting attachments may be mounted on the same sewing machine, and it is also obvious that

the machine may be equipped with any number of needles and a like number of cutters and loopers.

From the foregoing description it will be seen that the improved tufting attachment is of simple and novel construction, requires little modification of a standard sewing machine, and is well adapted for the purposes described.

What I claim as my invention is:

10 In a sewing machine tufting attachment wherein the machine has a reciprocating needle and the attachment includes a reciprocating looper and a revolute circular cutter mounted

on a normally fixed axis toward which the looper is reciprocated, an adjustable mounting for the cutter comprising a supporting member, an arm having its outer end angularly and longitudinally adjustably mounted on the supporting member, 5 a bearing block adjustably secured in the inner end of said arm, and a driven cutter shaft journaled in said bearing block, the circular cutter being mounted on said shaft to turn therewith and being axially adjustable on said shaft.

10

WILLIAM F. SCHMIEDEL.
